UNITED STATES PATENT OFFICE.

ERNST GESSNER, OF AUE, GERMANY.

WINDER FOR SPINNING-SPINDLES.

SPECIFICATION forming part of Letters Patent No. 441,000, dated November 18, 1890.

Application filed December 20, 1889. Serial No. 334,367. (No model.)

To all whom it may concern:

Be it known that I, ERNST GESSNER, of Aue, Saxony, Germany, have invented a new and useful Improvement in Winders for Spinning-Spindles, of which the following is a specification.

My invention relates to improvements in winders for spinning-spindles in continuous spinning-machines, and has reference especially to the invention presented in my patent, No. 409,957, dated August 27, 1889, upon which it is an improvement. The winders referred to in the said patent are composed of a thread-guide, an intermediate arm, and a guiding-piece embracing the spindle and bearing in frictional contact with the same.

My present invention has for its object an improved form of the guiding-piece of such winders, so as to make the winder of as little weight as possible for the purpose of making it capable of or adapted to running at high speed.

In the accompanying drawings, Figure 1 shows a winder applied to the rail and spindle. Fig. 2 shows a view of the winder in perspective. Figs. 3 to 5 are views similar to Fig. 1, showing various modifications of winders. Figs. 6 and 7 show in vertical section and plan views a device employed for holding the winder in its position while being lifted off from the spindle when the caps are to be doffed. Figs. 8, 9, and 10 are views similar to Figs. 1, 3, and 4, except that the winder is below the cap; and Figs. 11 and 12 show modified forms of the winder applied to the spindle and rail.

Fig. 1 shows the winder composed of the thread-guide L, arm L', and guiding-piece L², all being preferably made of one piece of sheet metal of as little weight as possible. The said guiding-piece consists of an oblong plate (see Fig. 2) with an opening, through which the spindle passes, and having its plane offset or crooked near its middle, so as to be held with its one half on the upper side of the plate A while the other half is sliding beneath. The plate A is fixed to the coppering-rail W. The opening in the guiding-piece is somewhat longer than the diameter of the spindle, and thus permits the winder to assume an inclined position to the axis of the spindle.

While the winder is at rest the two parts of the guiding-piece bear, respectively, on the upper and lower face of the plate A. By a one-sided strain, however, caused by the tension of the thread, the thread-guide L is drawn toward the spindle, and consequently the guiding-piece tilts somewhat, so that its two halves come out of contact with the upper and lower face of the plate A, while at the same time friction is produced between the guiding-piece and the revolving spindle, so that the winder is taken along not only by the thread, but also by friction from the spindle, whereby the tension of the thread is slackened to a certain degree. This lack of uniformity in the tension of thread arising during spinning is automatically regulated by the new winder in the following manner: At the start the thread-guide is drawn toward the spindle by the tension of the thread, and consequently friction with the spindle arises, as above mentioned. With the influence of friction the thread becomes slack, releasing the thread-guide and allowing it to be thrown away from the spindle by centrifugal action, so that the guiding-piece returns to its original position, bearing on the upper and lower faces of the plate A. It then acts as a brake, retarding the motion of the winder, and thus causes the thread to be tightened, which then draws the thread-guide again toward the spindle. The same process is then repeated.

Fig. 3 shows a similar winder, the guiding-piece L² having the same form as that shown in Fig. 1, besides being provided with a socket L³, embracing the spindle, which socket is somewhat larger than the spindle, so as to fit it loosely, in order to permit the arm L' to move to and from the spindle. For certain purposes the parts of the guiding-piece L² which slide on the upper and lower faces of the plate A are lined with some rough stuff, such as leather, felt, or other material, as shown at X in Fig. 4. This serves to act as a brake and increase the effect of retarding the motion of the winder.

Fig. 5 shows a winder the guiding-piece L² of which embraces the spindle below the cap and is held in the coppering-rail W in a similar manner to that shown in Fig. 1. A ring R is employed to prevent the arm L' from be-

ing thrown away too far from the spindle by centrifugal action. When the cops are full and are ready to be doffed, the coppering-rail W, with the winders shown in Figs. 1, 3, and 5 4, must be lifted off from the spindles.

In order to insure that the winders will remain in their position on the coppering-rail while being lifted off from the spindle, a device is necessary to be employed, as shown in 10 Figs. 6 and 7. W is the coppering-rail, having fastened to it the plate A, upon which the guiding piece L² of the winder is held, sliding on the upper and lower faces of the said plate, as described. The rail U is attached 15 to the coppering-rail W by hinge C, and a yielding plate O projects from the rail and has a slot for the spindle to pass through. The sliding frame or rest M, carrying the coppering-rail W, slides on a vertical rod or standard R, 20 and has connected to it a lever-arm H, held on pivot Y, through which lever-arm there passes the set-screw X, resting on the rail U. A spiral spring D is interposed between the two plates A and O, so as to hold the plate O 25 elevated, in order to admit of a free movement of the winder. A weight G, sliding on the vertical rod R, rests on a stud P. When the coppering-rail W, with the winders, is lifted off above the spindles for the purpose of doffing 30 the full cops, the end of the lever-arm H strikes against the under side of weight G, pushing the same in an upward direction, whereby it is slid upon the rod R. Owing to the action of the said weight, the set-screw X is pressed down on the rail U, the spiral spring D being 35 compressed and the plate O bearing on the guiding-piece L² of the winder, pressing it down onto the plate A, which is thus held in its position. In lowering the coppering-rail the 40 weight G will come in contact with and rest upon the stud P, so that the lever-arm H and consequently spiral spring D and plate O are released from pressure and the guiding-piece of the winder set free.

45 In Figs. 8, 9, and 10 I show, respectively, the same arrangement of parts as in Figs. 1, 3, and 4, except that the winder is supported from a point below the cop.

In Fig. 11 the winder, instead of being 50 stamped from sheet metal and having its plane crooked or offset, as in Fig. 2, is formed of two or more wraps or convolutions of wire where it surrounds the spindle, one end of which lies in one plane beneath plate A, and

the other portion of which lies in another 55 plane above the plate.

Fig. 12 shows a construction and arrangement of winder similar to Fig. 11, except that where the wire bears against the top and bottom of plate A it is provided with pads x. 60

With reference to the application of my new device illustrated in Figs. 8 to 12, I would state that I do not in this case make any claim to the broad method of winding shown in said figures independent of construction, (viz., 65 winding the thread upon the spindle by a winder held in the coppering-rail and in frictional contact with the spindle below the cop and gradually lowering said winder in addition to its traversing motion, whereby the cop 70 is built from the top downward,) as this broad method is claimed by me in a separate application, Serial No. 334,368.

Having thus described my invention, what I claim as new is— 75

1. The combination, with the spindle and the rail having plate A, of a winder consisting of a thread-guide, arm, and guiding-piece, the said guiding-piece having an opening to receive the spindle and formed with bearing- 80 surfaces in different planes, one adapted to bear against the bottom and the other against the top of plate A, substantially as and for the purpose described.

2. The combination, with a spindle and the 85 rail having plate A, of a winder composed of a thread-guide L, intermediate part L', and perforated guiding-piece L², having its plane crooked or offset and being in frictional contact with the spindle and held on the coppering- 90 rail, as described, so as to bear with one half of the said guiding-piece on the upper part of the coppering-rail plate while the other half slides beneath, substantially as and for the purpose described. 95

3. The combination, with the spindle and the winder, of the sliding frame M, carrying coppering-rail W, jointed lever H, and hinged rail U, provided with plate O and spring D, set-screw X, stem R, rest P, and weight G, 100 sliding on said stem and adapted to be struck by the lever H, substantially as and for the purpose described.

ERNST GEßNER.
